SHARPENING DEVICE

Theodore E. Brown, Berwyn, Ill.

Application November 8, 1935, Serial No. 48,830

3 Claims. (Cl. 51—187)

This invention relates to improvements in sharpening devices for sharpening knives, razors, scissors, and other like cutting tools, and one of the objects of the invention is to provide an improved device of this character in which the sharpening elements may be readily removed.

A further object is to provide an improved, simple, and efficient device of this character embodying a body to which the sharpening elements are secured for ready detachment, without the use of nails, screws, or the like, and which body is provided with handles at the ends thereof, thereby adapting the device for ready use by either right or left handed persons, the body being provided with sharpening elements on each side thereof, so that either side of the sharpener may be employed.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a perspective view of a device of this character constructed in accordance with the principles of this invention.

Figure 2 is a detail sectional view taken on line 2—2, Figure 1, on an enlarged scale.

Figure 3 is a detail sectional view taken on line 3—3, Figure 1, on an enlarged scale.

Figure 4 is a detail perspective view of one of the fastening clips.

Referring more particularly to the drawing, the numeral 10 designates generally a body portion which may be constructed of any suitable material, but preferably wood, and is comparatively thin with relation to its width.

The body may be of any desired length and the extremities thereof are preferably shaped to form handles 11, either one or both of which may be provided with an opening 12 by means of which the device may be suspended from the wall.

Within the body portion and opening through opposite faces thereof, are grooves 13 which extend transversely thereacross and open through opposite faces thereof. Both ends of each of these grooves are preferably open and the grooves may be arranged at any suitable point with respect to the length of the body, but they are preferably disposed adjacent the lower ends of the handles 11.

The sharpening elements 14 which are prefer-

ably in the form of flexible strips, may be formed of any suitable material, such as emery paper, sandpaper, or the like, and one of these strips is arranged adjacent each of the opposite faces of the body 10. The strips are preferably of a size and configuration to conform to the contour of the body 10 and are of such a length that the ends 15 thereof will project over the respective grooves 13, and a clip 16, preferably of a substantially U shaped formation having spring jaws 17, is provided for securing the sharpening strips 14 in position. The clips are placed in position by engaging over one of the edges of the body so as to force the ends 15 of the strips 14 into the grooves 13. The grooves 13 being open at both ends, renders it possible to place the clip in position from either side of the body, and when in position, the end 15 of the strip will be disposed between the jaws 17 of the clip and the bottoms of the respective grooves 13.

The grooves 13 are preferably of a width slightly greater than the width of the jaws 17 so as not to injure or cut the strips 14 by the placing of the jaws 17 of the clip, in position.

The jaws 17 are also preferably of a length 25 slightly less than the width of the body 10, so that the extremities of the jaws 17 will not project beyond the edge of the body 10.

The grooves 13 are also of such a depth and the jaws 17 of the spring clip 16 are of such a 30 thickness that when the clips are in position, the upper or outer surfaces of the clips will be substantially flush with the adjacent portions of the body.

With this improved construction it will be manifest that the device may be held by either handle 11 and either surface may be employed for the sharpening operation.

By the provision of the two handles 11, it is also manifest that when one edge of the sharpening elements 14 becomes worn, the device may be turned around and held by the other handle 11 to position the other edge to be used in the sharpening operation.

By the detachability of the clips 16 and the 45 sharpening strips 14, it will be manifest that the latter may be readily renewed when worn.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A sharpening device of the character described embodying an elongated substantially rectangular body comparatively thin with relation to its width, a handle at the end of said body, there being a groove of substantial width opening through the face of the body adjacent said handle and extending transverse to the longitudinal dimension of said body, a flexible strip of sharpening material contacting the face of the body with its end extending over said groove, a freely removable substantially U-shaped spring clip, the arms of said clip being of a substantial width, one of the arms of the clip seated in and substantially filling said groove and extending across said face of the body with the outer face of said arm substantially flush with the face of said body, the said flexible strip being disposed between said clip and the bottom of the groove, the arms of the clip urged transversely of the longitudinal dimension of said body, and the connecting portion of the clip between said arms contacting a longitudinal edge of said strip and also of the said body.
2. A sharpening device of the character described embodying an elongated body comparatively narrow with respect to its length and provided in opposite faces with open grooves of substantial width extending thereacross transverse to the length of said body, said grooves in the opposite faces being in alinement, a handle on the end of the body, a flexible strip of sharpening material contacting each face of said body with the end thereof extending over the respective grooves in said faces, and a freely removable and frictionally held clip substantially U-shaped, the arms of which are of substantial width and extend across said body transverse to the length thereof, said arms seated in the grooves and substantially flush with the respective faces of said body, with the ends of the flexible strips disposed

therebetween and the bottoms of the grooves, the arms resilient and portions thereof being normally spaced from each other for a distance less than the thickness of the body between the bottoms of the grooves whereby the stress created in the arms when the latter are seated in the grooves will force the flexible strips against the bottoms of the grooves.

3. A sharpening device of the character described embodying an elongated body comparatively narrow with respect to its length and provided in opposite faces with open grooves of substantial width extending thereacross transverse to the length of said body, said grooves in opposite faces being in alinement, a handle on the end of the body, a flexible strip of sharpening material contacting each face of said body with the end thereof extending over the respective grooves in said faces, and a freely removable and frictionally held clip substantially U-shaped, the arms of which are of substantial width and extend across said body transverse to the length thereof, said arms seated in the grooves and substantially flush with the respective faces of said body, with the ends of the flexible strips disposed therebetween and the bottoms of the grooves, the arms being resilient and portions thereof being normally spaced from each other for a distance less than the thickness of the body between the bottoms of the grooves whereby the stress created in the arms when the latter are seated in the grooves will force the flexible strips against the bottoms of the grooves, said arms being of a width slightly less than the width of the respective grooves, whereby the flexible strips passing over the edge of the grooves will be protected against being cut under the stress of said arms, the connecting portion of the clip between the arms abutting against a longitudinal edge of said body.
